US00D988346S

(12) **United States Design Patent** (10) Patent No.: **US D988,346 S**
(45) Date of Patent: **** Jun. 6, 2023**

(54) **DISPLAY SCREEN OF AN ELECTRONIC DEVICE WITH A GRAPHICAL USER INTERFACE**

(71) Applicant: **Varian Medical Systems, Inc.**, Palo Alto, CA (US)

(72) Inventors: **Filip Vojan**, Palo Alto, CA (US); **Brian Spatola**, Palo Alto, CA (US)

(73) Assignee: **VARIAN MEDICAL SYSTEMS, INC.**, Palo Alto, CA (US)

(**) Term: **15 Years**

(21) Appl. No.: **29/858,924**

(22) Filed: **Nov. 4, 2022**

Related U.S. Application Data

(60) Division of application No. 29/832,685, filed on Mar. 29, 2022, now Pat. No. Des. 975,112, which is a continuation of application No. 29/764,472, filed on Dec. 30, 2020, now Pat. No. Des. 951,274.

CLAIM

The ornamental design for a display screen of an electronic device with a graphical user interface, as shown and described.

DESCRIPTION

FIG. 1 illustrates a front view for a display screen of an electronic device with a graphical user interface, in accordance with a first embodiment of our design; and, FIG. 2 illustrates a front view for a display screen of an electronic device with a graphical user interface, in accordance with a second embodiment of our design. The broken line showing portions of the display screen and electronic device illustrates unclaimed environment and forms no part of the claimed design. The broken line showing portions of the graphical user interface illustrate unclaimed portions of the graphical user interface and forms no part of the claimed design.
